SCRAPER

Charles Le Bleu, Los Angeles, Calif., assignor to
The Slusser McLean Scraper Company, Sidney,
Ohio, a corporation of Ohio

Application December 18, 1933, Serial No. 702,892

3 Claims. (Cl. 37—126)

This invention relates generally to scrapers which are used for removing or displacing dirt, sand and other material, as in the leveling of ground, building roads, excavating, grading, etc., and more particularly to the type known as carry all scrapers in which the removed material may be transported from place to place.

Of the manifold objects of this invention, the prime one is to provide a scraper in which the removed material may be transported from place to place without spilling or losing any part of the load, as is now often the case, especially when transporting loose sand over long distances.

Another object is the provision of a scraper in which the material handling means and its actuating apparatus is carried by a primary frame structure supported at the forward end on a wheeled carriage and pivotally connected at the rear end to a secondary frame which is tiltably supported on a wheeled axle and carries a hydraulic power unit associated with the primary frame for effectively raising and lowering same.

A further object is the provision of a scraper in which a tiltible bowl or scoop has associated therewith a gate adapted to automatically swing toward the receiving side of the bowl upon elevating same from the operating position for retaining the removed material within the bowl, and swing away from the bowl upon tilting same for discharging the load. The gate is also automatically retained in the swung away position after the bowl is brought back to its operating position.

Another object is the provision of a scraper in which the bowl and the gate are operated by individual hydraulic power units, both of which are controlled by a single valve within the operator's reach.

As a further object, it provides a simple and compact yet substantial power controlled implement by which a surface operated upon may be scraped, graded, leveled and filled in to a desired degree, the removed material effectively retained within the implement for transportation and that the degree of operation together with the operative and inoperative positions of the implement may be controlled efficiently with a minimum of power by a single operator from a remote station.

With these and other objects in view the invention consists in the combination, correlation and construction of parts, members and features which will be described in the specification and will be finally pointed out in the claims.

Referring to the drawings:

Figure 1 is a plan view of a device embodying my invention.

Figure 2 is a section on line 2—2 of Figure 1, illustrating the implement in the scraping position.

Figure 3 is a section similar to Figure 2, illustrating the load carrying position of the implement.

Figure 4 is a section similar to Figure 3, showing the implement in the load discharging position.

Figure 5 is a section similar to Figure 4, illustrating the position of the bowl and gate before lowering into scraping position.

Figure 6 is a rear elevation of Figure 4.

Figure 7 is a perspective view of the gate.

Figure 8 is a plan view of a modified form of the device.

Figure 9 is a section on line 9—9 of Figure 8, illustrating the implement in the scraping position.

Figure 10 is a side elevation of Figure 8, illustrating the load carrying and discharging positions of the implement. Figure 11 is a diagrammatic view of the valve system for controlling the flow of fluid to the hydraulic power unit, with the valve plugs in their idle positions. Figure 12 is a cross sectional view taken through the valve controlling the flow of fluid to the bowl tilting cylinder and the gate raising and lowering cylinder, with the valve plug in a position to force the fluid into the rear ends of those cylinders to discharge the load. And Figure 13 is a cross-sectional view taken through the same valve, with the valve plug in a reverse position.

The objects outlined above are attained by the preferred and modified forms of embodiment of the invention shown in the drawings, which in a generic sense consists of material handling means and its actuating apparatus carried by a primary frame structure adapted for connection to a vehicle and supported at the forward end on a wheeled carriage, a secondary frame tiltably supported on a wheeled axle and pivotally connected to the rear end of the primary frame, actuating means mounted on the secondary frame and associated with the primary frame for controlling the vertical relation of the implement to the ground surface.

Referring to Figures 1 to 7 inclusive:

In a more specific sense, the invention exemplified by the preferred form in the accompanying drawings in a practical form of embodiment, is shown as comprising a primary frame 1 consisting of a rectangular portion 2 including the forward and rearward cross members 3 and 4 which are rigidly conjoined by side members 5, and

a forwardly extending bifurcated tongue 6 consisting of the spaced apart longitudinal members 7, which are secured at the rear ends to the forward cross member 3 and junctioned at the forward ends to form the depending leg 8 which in turn is swivably connected, as at 9, to the wheeled carriage 10. The wheeled carriage 10 is provided with a draft tongue 11 adapted for connection to a tractor as shown at 12.

10 A U-shaped secondary frame 13 comprising a cross member 14 having the forwardly extending side members 15 which are pivotally connected to the rear cross member 4 of primary frame 1, as shown at 16. To the under side of side members 15 and intermediate their ends are secured bearings 17 in which axle 18 carrying the wheels 19, is journaled.

15 A hydraulic power unit 20 is pivotally mounted, as at 21, on the cross member 14 of the secondary frame 13 and has its piston rod 22 pivotally connected to brackets 23, as shown at 24, which are welded or otherwise secured to the rear cross member 4 of the primary frame 1.

20 Fluid under pressure is supplied through hose lines 25 and 26 to the hydraulic power unit 20 from a pump 25a on the vehicle and is controlled by a plug valve 26a within the reach of the operator. The vehicle, being conventional, is not illustrated.

25 30 The secondary frame 13 is tiltable by virtue of the bearings 17 on axle 18 and by reason of its pivotal connection to the rear end of the primary frame 1 imparts a raising and lowering motion to the primary frame 1 thereby controlling the degree of operation of the implement. The hydraulic power unit 20 by reason of its connections 21 and 24 to the secondary and primary frames 13 and 1 respectively, provides the motive power for tilting the secondary frame 13 by 35 spreading and contracting the distance between the connections 21 and 24.

35 40 A bowl or scoop 27, provided with the usual cutting edge 28 and side wings 29, is pivotally supported within the rectangular portion 2 of the primary frame 1 by means of trunnions 30 on side wings 29 and pivoted in bearings 31 on the side members 5. A hydraulic power unit 32 pivotally mounted in brackets 33, as shown at 34, has its piston rod 35 connected to the bowl 27 as shown at 36. The brackets 33 are secured to the longitudinal members 7 of the bifurcated tongue 6.

45 50 A gate 37 comprising a scoop 38 having a cutting edge 39 and at each end thereof the side wings 40. The upper edge of the scoop 38 is reinforced longitudinally by means of the angles 41 and 42, and transversely by web 43. The side wings 40 are provided with upwardly extending lobes 44, which are adapted to be pivotally connected to brackets 45 on the side members 5. A 55 hydraulic power unit 46, positioned within the space 47 between the longitudinal members 7 of the bifurcated tongue 6 and pivotally mounted in brackets 48, as shown at 49, on the junction forming the leg 8, has its piston rod 50 pivotally connected to the top edge of scoop 38 as illustrated at 51.

55 60 Fluid under pressure is supplied to the hydraulic power units 32 and 46 through hose lines 52 and 53 from a pump 52a.

65 70 The hose lines 52 and 53 lead to the forward and rearward ends, respectively, of the hydraulic power unit 32. Branch conduits 54 and 55 by virtue of the Y connections 56 and 57 interposed in hose conduits 52 and 53, respectively, supply fluid 75 under pressure to the forward and rearward ends

of the hydraulic power unit 46. The supply of fluid to both of the hydraulic power units 32 and 46 is controlled by a single conventional plug valve 53a within the reach of the operator.

75 It will be noted that the trunnions 30 are secured to side wings 29 forward of the center of gravity of bowl 27 so that the weight of the bowl at the rear side of trunnions 30 is greater than the weight of the gate 37. The reason for this distribution of weights will be pointed out subsequently.

80 85 When the bowl 27 is in the scraping position, as illustrated in Figure 2, the gate 37 is swung away from the receiving side of the bowl and is retained in that position during the scraping operation. When the bowl 27 is filled with the removed material and it is desired to transport this material to another place, the valve 53a governing the supply of fluid to hydraulic power units 32 and 46 is manipulated to the position shown in Figure 13 to force the fluid through conduit line 52 and its branch 54 simultaneously to the forward ends of cylinders 32 and 46, respectively. Inasmuch as the piston of hydraulic power unit 32 is at the end of its rearward stroke when the implement is in this position, the hydraulic power unit 46 will now operate to close gate 37 against to bowl 27 for retaining the accumulated material. Now the valve 26a actuating the hydraulic power unit 20 is manipulated to raise the bowl 27 off the ground surface for transportation, as illustrated in Figure 3.

90 95 For discharging the load, the valve 53a governing the supply of fluid to hydraulic power units 32 and 46 is manipulated to the position shown in Figure 12 to force the fluid through conduit line 53 and its branch 55 simultaneously to the rearward ends of cylinders 32 and 46, respectively. Here, by virtue of the differential in resistance due to the above mentioned weight variations, the hydraulic power unit 46 acts first, thereby opening gate 37. When gate 37 is fully opened the piston within the cylinder 46 has reached the end of its stroke and then the full pressure from conduit line 53 is directed against the piston within cylinder 32 to tilt bowl 27 for discharging, as illustrated in Figure 4.

100 105 To return the bowl 27 to its original position, the valve 53a governing the supply of fluid to the hydraulic power units 32 and 46 is again manipulated to force the fluid through conduit line 52 and its branch 54 simultaneously to the forward ends of cylinders 32 and 46, respectively. Now by reason of the fact that the bowl 27 is heavier at its rear side than the gate 37, it has a greater tendency to swing back into its original position by gravity than has the gate 37 thus causing the hydraulic power unit 32 to act first. When the piston within the cylinder 32 is near the end of its stroke the fluid supply is shut off, thus preventing the actuation of power unit 46 and retaining gate 37 in the open position as shown in Figure 5 where the implement is illustrated in the position just prior to lowering into the scraping position.

110 115 It has been pointed out above that the tilting of the bowl 27 and operation of gate 37 can be controlled by a single valve, in this instance the valve 53a, by reason of weight differentials between the back of bowl 27 and the gate 37. The same function, however, may be obtained when the weights of bowl 27 and gate 37 are balanced, by having the cylinder 46 of a larger diameter than the cylinder 32.

Referring to Figures 8 to 10 inclusive:

The invention exemplified by the modified form in these figures in a practical embodiment is shown as comprising a primary frame 1a consisting of a rectangular portion 2a including the forward and rearward cross members 3a and 4a which are rigidly conjoined by side members 5a, and a forwardly extending tongue 6a of which the depending leg 8a is swivably connected at 9a, to the wheeled carriage 10a. The wheeled carriage 10a is provided with a draft tongue 11a adapted for connection to a tractor as shown at 12a.

A U-shaped secondary frame 13a comprising a cross member 14a having the forwardly extending side members 15a which are pivotally connected to the rear cross member 4a of primary frame 1a, as shown at 16a. To the under side of side members 15a and intermediate their ends are secured bearings 17a in which axle 18a carrying the wheels 19a, is journaled.

A hydraulic power unit 20a is pivotally mounted, as at 21a, on the cross member 14a of the secondary frame 13a and has its piston rod 22a pivotally connected to brackets 23a, as shown at 24a, which are welded or otherwise secured to the rear cross member 4a of the primary frame 1a.

Fluid under pressure is supplied through hose lines 25a and 26a to the hydraulic power unit 20a from a pump similar to the pump 25a on the vehicle and is controlled by a valve similar to the valve 26a within the reach of the operator. The vehicle, being conventional, is not illustrated.

The secondary frame 13a is tilttable by virtue of the bearings 17a on axle 18a and by reason of its pivotal connection to the rear end of the primary frame 1a imparts a raising and lowering motion to the primary frame 1a thereby controlling the degree of operation of the implement. The hydraulic power unit 20a by reason of its connections 21a and 24a to the secondary and primary frames 13a and 1a respectively, provides the motive power for tilting the secondary frame 13a by spreading and contracting the distance between the connections 21a and 24a.

A bowl or scoop 58, provided with an arcuate back 59, side wings 60 and a removable bottom 61 which has the usual cutting edge 62, is pivotally supported within the rectangular portion 2a of the primary frame 1a by means of trunnions 63 on the side wings 60 and pivoted in bearings 64 on the side members 5a.

The arcuate back 59 may be reinforced longitudinally along its lower and upper edges by angles 65 and 66, and transversely by web 67.

The arcuate back 59 may be provided with a cutting edge 68 to be used for leveling when bottom 61 is removed.

A hydraulic power unit 69 pivotally mounted in brackets 70, as shown at 71, has its piston rod 72 connected to the bowl 58 as shown at 73. The brackets 70 are secured to the forwardly extending tongue 6a.

Having thus described my invention I claim:

1. In an implement of the type described, in combination with a wheeled frame adapted to be raised and lowered, a scraper bowl pivotally

mounted on said frame, a gate pivotally hung on said frame, the weight of the bowl at the rear side of its pivot being greater than the weight of the gate, means for raising the bowl off the ground for transportation after the gate is closed 5 against the bowl to retain the accumulated material therein, a hydraulic cylinder pivotally mounted in said frame, a piston reciprocable in said cylinder and pivotally connected at its outer end to the rear end of said bowl, a second hydraulic cylinder also pivotally mounted in said frame, a piston reciprocable in the latter cylinder and pivotally connected at its outer end to the upper front end of said gate, conduit means 10 for conducting fluid under pressure to the rear 15 ends of said cylinder, and a valve permitting the fluid to flow through said conduit means simultaneously to the rear ends of both cylinders, first to move the piston inwardly in the second cylinder to raise the gate by virtue of the differential 20 resistance due to said weight variation, and when said second piston has reached the end of its stroke the piston in the first cylinder will be actuated by said fluid to tilt the bowl to discharge the material therefrom. 25

2. A leveling device comprising a primary frame structure adapted for connection to a tractor, a scoop mounted within said primary frame, a secondary frame, a wheeled axle mounted intermediate the ends of said secondary frame, pivotal means for connecting the forward end of said secondary frame to the rear end of said primary frame, hydraulic power means interposed between the rear ends of said primary and secondary frames for imparting rocking 35 movement to said secondary frame thereby raising and lowering said primary frame.

3. In an implement of the type described, in combination with a wheeled frame adapted to be raised and lowered, a scraper bowl pivotally 40 mounted on said frame, a gate pivotally hung on said frame, the weight of the bowl at the rear side of its pivot being greater than the weight of the gate, means for raising the bowl off the ground for transportation after the gate is closed 45 against the bowl to retain the accumulated material therein, a hydraulic cylinder pivotally mounted on said frame, a piston reciprocable in said cylinder and pivotally connected at its outer end to the rear end of said bowl, a second hydraulic cylinder also pivotally mounted in said frame, a piston reciprocable in the latter cylinder and pivotally connected at its outer end to the upper front end of said gate, a conduit line having two branches, one branch leading to the front 55 end of the first cylinder and the other branch to the front end of the second cylinder, a second conduit line having two branches, one branch leading to the rear end of the first cylinder and the other branch leading to the rear end of the second cylinder, and a valve for controlling the flow of fluid under pressure through either conduit line, to convey fluid simultaneously to the front ends of said cylinders, or simultaneously to the rear ends of the latter. 60 65

CHARLES LE BLEU.
